[57] CLAIM

The ornamental design for a high-pressure discharge lamp, as shown and described.

DESCRIPTION

FIG. 1 is a front perspective view of a high-pressure discharge lamp showing my new design;

FIG. 2 is a front elevational view thereof;

FIG. 3 is a side elevational view thereof as seen from the left of FIG. 2;

FIG. 4 is a bottom plan view thereof;

FIG. 5 is a rear elevational view thereof;

FIG. 6 is a side elevational view thereof as seen from the right of FIG. 2.

FIG. 7 is a top plan view thereof;

FIG. 8 is a front perspective view of a second embodiment of my new design;

FIG. 9 is a front elevational view thereof;

FIG. 10 is a side elevational view thereof as seen from the left of FIG. 9;

FIG. 11 is a bottom plan view thereof;

FIG. 12 is a rear elevational view thereof;

FIG. 13 is a side elevational view thereof as seen from the right of FIG. 9.

FIG. 14 is a top plan view thereof.

The stippled areas in the drawings illustrate holding cement, having a different texture than the remainder of the base which, usually is made of ceramic material. The interior leads are shown in broken lines for illustrative purposes only.
